CLAIM

The ornamental design for a dog toy, as shown and described.

DESCRIPTION

FIG. 1 is a top front left perspective view of a dog toy in accordance with our new design;

FIG. 2 is a bottom rear right perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof; and,

FIG. 8 is a front elevation view thereof.

The broken lines shown in the drawings illustrate portions of the dog toy that form no part of the claimed design.

1 Claim, 5 Drawing Sheets
